HENRY H. ROYER, OF ROANOKE, VIRGINIA, ASSIGNOR OF ONE-HALF TO RICHARD P. ROYER, OF ROANOKE, VIRGINIA.

METALLIC PACKING.

1,216,503.

Specification of Letters Patent. Patented Feb. 20, 1917.

Application filed January 8, 1916. Serial No. 70,923.

To all whom it may concern:

Be it known that I, HENRY H. ROYER, a citizen of the United States, residing at Roanoke, in the county of Roanoke and 5 State of Virginia, have invented certain new and useful Improvements in Metallic Packing, of which the following is a specification.

This invention relates to steam packing for piston rods, valve rods or other reciprocating or rotating rods or shafts where it is desired to prevent the escape of steam or other fluids from a pressure chamber. The particular object of the same is to provide a simple form of metallic packing for such 10 purposes and to provide improvements generally in this art. With these objects in view, the invention consists in the combination, formation and arrangement of the various parts as herein described and as particularly claimed.

The accompanying drawings show a preferred embodiment of my invention and in these drawings, Figure 1 is a side elevational view, partly in section, showing the application 15 of my packing to the piston rod of an ordinary steam engine. Fig. 2 is an end elevational view of the same, the piston rod being shown in section. Fig. 3 is an end elevational view of the metallic packing, looking 20 from the exterior toward the interior of the steam cylinder. Fig. 4 is a similar view of this packing, seen in the opposite direction. Fig. 5 is a transverse section of this metallic 25 packing taken on the line A B, Fig. 4. Fig. 6 is a broken sectional view through the packing gland, taken on the line C D, Fig. 2.

Referring now to these drawings wherein like parts are similarly designated, 1 represents the piston rod of an ordinary steam 30 engine and 2 a portion of the cylinder head. Secured to the cylinder head 2 by means of the stud bolts 4 and the nuts 5 is a gland 3, the same being drawn firmly against the outer face of the cylinder head by means of 35 the aforesaid bolts and nuts, the copper ring 18 forming a steam-tight joint between these parts.

The cylinder head 2 is pierced at 6 to accommodate the piston rod 1 in its reciprocations. At 7 this cylinder head 2 is counterbored concentric with the piston rod 1 and the opening 6 so as to form a cavity for the coil spring 16, the bottom of the counterbore 50 providing a shoulder or abutment 22 against which this coil reacts.

The gland 3 is similarly pierced at 8 to accommodate the piston rod 1, both of the holes 6 and 8 being of sufficient size to allow the passage of the customary collar 17 on the exterior portion of the piston rod. The 60 gland 3 is likewise counterbored from its inner toward its outer end so as to form the cavity 9, the same being concentric with the piston rod 1 and the hole 8, and of larger diameter than the cavity 7. The bottom of 65 the counterbore in the gland forms a shoulder or abutment 10 for cooperation with the parts of the piston packing.

The packing proper is formed of a composite ring of Babbitt or similar metal which 70 will become slightly plastic under the influence of steam, this ring being made up of 3 or more segments. I have found that if this ring is made up of 2 sections there will be bending of the sections when compressed 75 against the piston rod and consequently more frequent leakage of steam. By making this packing ring of 3 segments or more it will be seen that the radial force of the steam pressure will force these sections against the 80 rod without such bending. This packing ring I make of a composite cross section consisting of a segmentally cut ring 11 of square cross section, with a similarly cut L-section ring 12. The square section ring 11 snugly 85 encircles the piston rod 1, the L-section ring being arranged so that the narrow edge of one of the legs snugly encircles the piston rod, the internal angle of the L accommodat- 90 ing the square section of the ring 11. Thus the two portions 11 and 12 complement each 95 other to form a complete square or rectangular section.

The various segmental sections of this composite ring are assembled around the 95 piston rod and a band spring 13 is then applied externally of this complete ring in order to prevent the disarrangement of the various parts after assembly.

This composite ring is positioned longitudinally of the piston rod between a vibrating ring 24 and a follower 25 which are made of harder metal. The vibrating ring and follower are duplicates of each other and like the packing are made up of complementary 105 sections, the portion 14 of each being of L-shape in cross section with a substantially square section ring 15 fitting into the angle of the L and completing a composite square or rectangular section for these parts. In 110

each instance, the L-section 14, which encircles the piston rod with some slight clearance, is made in halves, the cut being shown at 19, in order that the same may be positioned around the piston rod without the necessity of excessive clearance being provided so as to pass over the collar 17. The square-section portion 15 of the vibrating ring and of the follower is made of a complete ring, the internal diameter of the same being of sufficient size to slip over the collar 17. This continuous ring 15, when applied over the halves of the L-shaped portion 14, holds the parts of the composite ring in their correct relationship, and completes the square or rectangular section.

These composite vibrating and follower rings 24 and 25 when positioned on the piston rod are turned in reverse directions, the vertical leg of the L-ring 14 being turned in each instance toward the composite packing ring and presenting a larger face against the same than were the rings 24 and 25 turned the opposite ways. In case they were turned this latter way there would be a possibility of the rings 15 moving outward over the packing ring after the latter has worn down and thus allow the parting of the halves of the L-rings 14. In my arrangement such a possibility is avoided. The other flat leg of the L is turned toward the rod so as to present a continuous face for wear and also allow for the larger internal diameter of the complete ring 15 necessary to pass over the collar 17.

It will be seen from Fig. 1 that the outer face of the vibrating ring 24 abuts the shoulder 10 of the gland 3. The inner follower 25 is slightly removed longitudinally of the rod from the vibrating ring, and the metallic packing proper is inserted between the two. The coil spring 16 then extends direct from the shoulder 22 of the piston head to the inner face of the follower and forces this follower outwardly at all times, compressing the metallic packing proper between the follower and the vibrating ring.

The depth of the counterbored portion of the gland 3, or the distance from the shoulder 10 to the inner end of the gland 3, is such that the combined lengths, longitudinally of the piston rod 1, of the vibrating ring, the follower and the metallic packing, when assembled, will be less than the depth 55 of the cavity 9, thus providing a steam passageway 23 from the cavity 7 to the cavity 9. In other words, the cavity 7 and the cavity 9 together form a two-part connected pressure compartment in open communication with 60 the steam vessel or cylinder, the outer part accommodating the packing, etc., and the inner part the spring. And the follower 25 is adjacent to but does not extend to the inner or spring portion of this pressure compartment in order that the pressure fluid may

have free access from one portion of this compartment to the other around the inner end of the follower. And the follower ring is of larger diameter than the cavity 7 so that an abutment is presented to prevent the retreat of the parts with the piston rod by compressing the spring 16, this spring being of less diameter for its full length than the cavity 7 so as to allow its being compressed entirely beyond the outer face of the head. 75 By this means, the use of a pierced thimble between the spring and the follower or the use of a distance sleeve encircling the spring such as has heretofore been necessary has been avoided and the end room necessary 80 for the application of the packing and the number of parts greatly reduced.

It will now be seen that the steam pressure will act directly against the inner end of the follower to assist the spring 16 in 85 tightly compressing the metallic packing between the follower and the vibrating ring as well as to seat the vibrating ring against the shoulder 10 while at the same time steam pressure will be exerted circumferentially 90 of the metallic packing to compress it radially inwardly against the piston rod 1; thus the steam pressure itself serves to keep the packing joint tight, the segmental formation of the metallic packing allowing this 95 radial compression, and the heat of the steam keeping the metallic packing in condition to respond to the radial and the endwise pressure.

Thus I have provided a packing unit with 100 a maximum of duplicate parts and in which there will be greatly reduced wear on the sliding piston rod because of the relatively small pressure area reacting against the piston rod in a radially-inward direction. At 105 the same time the parts are all so arranged that they may be readily assembled and dismantled without sticking of parts due to gummed oil or carbon deposit.

Slight clearance is allowed between the 110 segmental portions of the metallic packing rings 11 and 12 so that the parts may be at liberty to move inwardly under the influence of the steam pressure as they wear away.

The outer face of the portion 14 of the vibrating ring is ground against the shoulder 10 so as to provide a steam tight joint at this point, the steam pressure keeping the vibrating ring tight up against the shoulder. The counterbored portion 9 of the gland 3 is continued at 21 to some little distance below the shoulder 10 so that dirt and other foreign matter may not prevent the proper seating of the vibrating ring against 125 the shoulder 10.

It will be realized that the wear of the cross-head outside the cylinder and the wear of the piston inside the cylinder will cause appreciable transverse movement of the pis- 130

ton rod within the cylinder head 2 and the gland 3. The flat bearing of the outer face of the vibrating ring 24 against the shoulder 10 allows this transverse movement and on this account is used instead of a ball joint arrangement. At the same time a steam joint is maintained. It is desirable, however, that these sliding surfaces be lubricated; hence I provide in the shoulder 10 the annular oil groove 26 which is formed concentric with the hole 8. Communicating with this oil groove is an oil passageway 27 leading from a cavity 28 in the outer face of the gland 3.

15 This cavity 28 is internally threaded at 29 to accommodate the threads of a commercial street L 30 which serves as an oil cup. Compressed between the end of the street L and the bottom of the cavity 28 is a bunch of 20 curled hair which serves as an oil strainer. This particular construction is used, however, because it performs another and more important function. It occasionally happens that a steam leak will occur along the piston 25 rod, past the metallic packing, or around the vibrating ring between the same and the shoulder 10. Without this arrangement both leaks would be manifested through the hole 8 in the gland 3 and it would be difficult to determine which of the two locations 30 is responsible for the leak. The annular groove 26 and the communications therefrom to the exterior just described enable 35 definite determination of the seat of the trouble inasmuch as vibrating ring leaks will follow out to and through the street L while piston rod leaks will be manifested as usual through the hole 8.

In order that the studs 4 and nuts 5 may 40 exert a direct and straight pull in forcing the gland 3 against the head 2, short pieces of copper wire at 20 may be laid between the gland and the piston head just outside of these bolts, these pieces of copper wire being applied in a similar manner to that of 45 the complete circle of copper wire 18.

Having thus described my invention, what I claim and desire to secure by Letters Patent is:

50 1. A metallic packing for steam piston rods or the like, comprising in combination, a steam vessel, a pierced head for the same, a piston rod passing through the said pierced head, a counterbored cavity in the exterior face of the said head, the same being concentric with and of slightly greater diameter than the said pierced head, a gland detachably secured to the outer face of the said head forming a steam-tight joint, the 55 said gland being pierced concentric with the hole in the said head to accommodate the said piston rod and having a concentric counterbored portion in its inner face of larger diameter than the counterbore in the 60 said head and forming with the same a two-

part, connected, steam cavity, a vibrating ring encircling the said piston rod and having a flat, end face which co-operates with the bottom of the counterbore in the said gland to form a flat steam joint, a follower 70 ring of larger diameter than the counterbore in the said head encircling the said piston rod and positioned along the same in spaced relationship with the said vibrating ring and having its inner face formed to overlap and abut the outer face of the said head when the piston rod and the said follower retreat, a composite, sectional, metallic packing ring, formed of a yieldable metal, encircling the said piston rod and 75 adapted to be compressed radially against the same by the steam pressure and being disposed longitudinally of the rod in the space between the said vibrating and follower rings, the said rings being so formed 80 and assembled around the piston rod as to form a steam abutment longitudinally of the piston rod whereby the internal steam pressure will force in turn the follower ring outwardly against the packing ring, the 85 packing ring against the vibrating ring, and the vibrating ring against the flat face joint, the assembled vibrating ring, packing and follower ring being of less length longitudinally of the rod than the length of the 90 outer portion of the said two-part steam cavity and being contained entirely within the said outer portion thereof, and a coil spring encircling the said piston rod within 95 the counterbored portion of the said head 100 and reacting longitudinally against the bottom of the counterbore at one end and against the follower ring at the opposite end, the said spring being of less diameter 105 for its full length than the counterbore in the said head, the vibrating ring and follower ring each being formed of L-shaped half-ring sections with complementary complete rings of rectangular shape and each being positioned so that one of the flat legs 110 of the L bears against the adjacent side of the said metallic packing ring, the other flat leg of each ring being turned toward the said piston rod.

2. A metallic packing for steam piston 115 rods or the like, comprising in combination, a steam vessel, a pierced head for the same, a piston rod passing through the said pierced head, a gland detachably secured to the outer face of the said head forming a 120 steam-tight joint, the said gland being pierced concentric with the hole in the said head to accommodate the said piston rod and having a concentric counterbored portion in its inner face, the bottom of the said 125 counterbore terminating in a flat shoulder, a vibrating ring encircling the said piston rod and having a flat, end face which co-operates with the flat bottom of the counterbore in the said gland to form a flat, steam 130

joint, a follower ring encircling the said piston rod and positioned along the same in spaced relationship with the said vibrating ring, a composite, sectional, metallic packing ring formed of a yieldable metal encircling the said piston rod and adapted to be compressed radially against the same by the steam pressure and being disposed longitudinally of the rod in the space between the said vibrating and follower rings, the said rings being so formed and assembled around the piston rod as to form a steam abutment longitudinally of the piston rod whereby the internal steam pressure will force in turn the follower ring, the packing

ring and the vibrating ring outwardly against the said flat shoulder of the counterbore, an annular groove in the flat face of the bottom of the said counterbore, the said groove being adapted to be covered by 20 the adjacent face of the said vibrating ring, and a passageway extending from the said groove to the exterior of the said gland.

In testimony whereof I affix my signature in presence of two witnesses.

HENRY H. ROYER.
